digester vessels built to withstand high steam pressure be used. Suitable digester vessels will now be described with reference to Figs. 2 to 6 inclusive of the drawing.

Preferably, the dimensions of the digester used are determined by a consideration of the desired reaction. Thus, if the reaction is one which takes place slowly, the digester vessel should be long enough to permit the ore to remain in it until the reaction goes substantially to completion. As shown in Figs. 2 and 2a, the digester D is an elongated, generally cylindrical vessel mounted horizontally and is provided with end caps 10, 11. The vessel D is rotatable about its longitudinal axis and is rotated by a train of gears 12, 13, driven by a motor 14. Idler gears 15, 16, may be provided for stability. The digester vessel D is provided with continuous feeding means F and continuous discharge means R.

The continuous feeding means F comprises an axially located inlet pipe 17 through which the slurry of ore and digestant may be admitted axially into one end of the digester D from a supply pipe 18. A tubular shaft 19 which passes through the cap 10 of the digester D and a collar 20 joined thereto is journalled in a packing gland 21 so that the shaft 19 will rotate with the digester D. The gland 21 is provided with packing 22 in sealing contact with the tubular shaft 19, and a gland nut 23 is provided to compress the packing 22. Steam may be admitted axially into one end of the digester D through the annular space 24 formed between the tubular shaft 19 and the slurry inlet pipe 17 from a supply pipe 25 joined to the gland 21.

The slurry inlet pipe 17 and the annular space 24 communicate with a T-shaped baffle 26 located within the digester D and provided with a closed end 27 and an open end 28. The baffle 26 is mounted on a tubular shaft 29 which is secured to a collar 30 secured to the cap 10 of the digester vessel D. Thus, the baffle 26 will rotate with the digester vessel D.

To permit the continuous removal of digested material axially from the other end of the digester D, the digester is provided with continuous discharging means R, illustrated in detail in Figs. 5 and 6, comprising a spiral scoop pipe 31 mounted within the end cap 11 of the digester vessel D. The scoop pipe 31 is provided with an open end 32 adapted to scoop accumulated slurry from the cap 11. The other end of the scoop pipe 31 is joined to a discharge pipe 33 located at the longitudinal axis of the vessel D and rigidly mounted on the inside of the cap 11 and on a perforated plate 34 provided in the digester vessel D, the scoop pipe 31 being located between the perforated plate 34 and the end cap 11. This mounting of the scoop pipe 31 permits it to rotate with the digester vessel D and the open end 32, being located adjacent to the inner cylindrical surface of the vessel D, and extending in the direction of rotation of the latter, will scoop hot slurry into the pipe 31 and discharge such slurry through the outlet pipe 33 as the vessel rotates. The discharge pipe 33 is joined to the cap 11 and communicates with an opening 35 therein and with an external discharge pipe 36 provided with a valve 37. The discharge side of the valve 37 is connected by suitable piping including a flanged joint 38 and a flexible coupling 39 to a second valve 40, the flexible coupling 39 being used to provide flexibility in the discharge piping and the joint 38 being inserted to provide for dismantling the piping for repairs if necessary.

A pipe 41 from the discharge side of the valve 40 is journalled in a gland 42 provided with packing 43 in sealing contact with the discharge pipe 41. The gland 42 is provided with a nut 44 for compressing the packing 43. Suitable stationary piping 45, having a part coaxial with and communicating with the rotating pipe 41 may be connected to a flange of the gland 42 for delivery of the hot digested material to a condenser C.

The condenser C, illustrated in Fig. 2a of the drawing, comprises a tank 46 having a slurry inlet pipe 47 which is connected to the gland 42 by suitable piping 45 thereby providing for the delivery of digested material from the vessel D to the condenser C. The slurry inlet pipe 47 leads to an elongated stationary pipe or cooling coil 48 in the tank 46 provided with an outlet 49. Cooling water is circulated through the tank 46 through an inlet 50 and an outlet 51. The cooling water may be agitated by an agitator 52 driven by a motor 53.

In operation, the digester D is rotated by the motor 14 acting through the gears 12, 13. A slurry of ore material and digestant is fed through the slurry inlet pipe 17 from the slurry supply pipe 18 while steam is admitted from the steam supply pipe 25 through the annular space 24. The steam and slurry are delivered into the rotating baffle 26 and through its open end 28 to the interior of the digester D. By this method of delivery all of the slurry is delivered so that it will pass through the digester D in a predetermined path of travel at a rate dependent on the rotation of the digester.

Rotation of the digester D causes the slurry to move through the digester and to be delivered through the perforated plate 34 which effectively bars the passage of large lumps of material to the end cap 11. The scoop pipe 31 rotates with the digester D, and its open end 32 scoops digested material from the end cap 11, discharging it through the pipe 33.

The digested material removed from the digester D is delivered through the discharge piping and the slurry inlet 47 to the cooling coil 48 of the condenser C. As the slurry passes through the cooling coil 48, it is cooled to a temperature below 100° C., and the steam present is condensed. Passage of the slurry through the coil 48 and the consequent cooling of the slurry to below its boiling point cause the pressure to be reduced so that the slurry may be discharged at atmospheric pressure through the outlet pipe 49 to the next step in the process, filtration.

The apparatus of the invention makes possible the efficient and economical separation of valuable metals from ores. It is particularly advantageous in providing for the continuous treatment of ores; large quantities of ore may be digested at low cost compared with the cost of batch treatment. The recycling of partially digested ore increases the efficiency of separation, making possible the recovery of a high percentage of the valuable metal from the ore, and also leads to the production of a purer product than can be obtained by mechanical separation methods. The invention thus provides an apparatus for treating low grade ores, such as domestic scheelite, to recover valuable metals therefrom at low cost, and thereby, particularly in the case of tungsten, provides for an increased domestic supply of valuable metal.

It has been found that the digestion of scheelite using the apparatus and method of the invention is most efficiently carried out at a tempera-

ture above about 125° C., preferably in the neighborhood of 200° C. using as a digestant an alkaline material, for example, an aqueous solution of sodium carbonate. Under these conditions, recoveries of tungsten as high as 96% to 100% have been obtained.

Although the invention has been described with particular reference to the treatment of tungsten ores, it is applicable to the treatment of any ores of the type which are treated by chemical methods involving digestion. And although specific details of construction of the apparatus forming one embodiment of the invention have been given, modifications therein will be apparent. Such modifications are within the scope of the invention.

This application is a continuation of my application Serial No. 425,367, filed January 1, 1942, now forfeited.

What is claimed is:

1. In a digester for treating a slurry of comminuted ore material and aqueous digestant, the combination of an elongated, substantially horizontal, generally cylindrical vessel mounted for rotation about its longitudinal axis; mechanism for rotating said vessel about said axis; means for feeding such slurry into one end of said vessel while the latter is rotating; means for applying heat to the slurry within said vessel while the latter is rotating; and means constructed and arranged to discharge hot slurry from the other end of said vessel while the latter is rotated by said mechanism, such discharging means comprising a pipe rotatable with said vessel and located within said vessel adjacent the other end thereof, said pipe having its inlet end located adjacent the inner cylindrical surface of said vessel and extending in the direction of rotation of said vessel so as to scoop hot slurry into said pipe as said vessel rotates, said pipe having its outlet located at the longitudinal axis of said vessel.

2. In a digester for treating a slurry of comminuted ore material and aqueous digestant, the combination of an elongated, substantially horizontal, generally cylindrical vessel mounted for rotation about its longitudinal axis; mechanism for rotating said vessel about said axis; means constructed and arranged to feed both slurry and steam into one end of said vessel while the latter is rotated by said mechanism; and means constructed and arranged to discharge hot slurry from the other end of said vessel while the latter is rotated by said mechanism, such discharging means comprising a substantially helical pipe rotatable with said vessel and located therein adjacent the other end thereof, said pipe having its inlet end located adjacent the inner cylindrical surface of said vessel and extending in the direction of rotation of said vessel so as to scoop hot slurry into said pipe as said vessel rotates, said

pipe having its outlet located at the longitudinal axis of said vessel.

3. In apparatus for treating a slurry of comminuted ore material and aqueous digestant, the combination of an elongated, substantially horizontal, generally cylindrical, closed vessel mounted for rotation about its longitudinal axis and built to withstand high steam pressures; means for rotating said vessel about said axis; axially located inlet means extending into one end of said vessel for feeding slurry thereinto while said vessel is rotating; means for applying heat to said slurry within said vessel while the latter is rotating; a pipe extending from within the other end of said vessel outwardly and axially therethrough for discharging hot slurry from said rotating vessel; and a conduit outside said vessel and communicating with said pipe to receive hot slurry discharged from the latter while the vessel is rotating, said conduit being of such length that said slurry will be discharged therefrom at substantially atmospheric pressure when cooling water is applied to said conduit; and means associated with said conduit for applying cooling water to the latter.

4. In apparatus for treating a slurry of ore material and a digestant, the combination of an elongated, substantially horizontal, generally cylindrical vessel mounted for rotation about its horizontal axis; mechanism for rotating said vessel about said axis; means for feeding such slurry axially into one end of said vessel while the latter is rotating; means for applying heat to the slurry within said vessel while the latter is rotating; a conduit pipe rotatable with and extending within and axially from the other end of said vessel, the inner end of said pipe being so arranged and constructed off the axial line that hot slurry is discharged therethrough while the vessel is rotating; a stationary cooling coil outside said vessel and comprising a stationary pipe having a part thereof coaxial with and communicating with said rotatable pipe to receive the hot slurry discharged by the latter while said vessel and rotatable pipe are rotated; and means associated with said cooling coil for applying cooling water to the latter to cool the hot slurry flowing therethrough.
